JUG OR SIMILAR ARTICLE

Floyd E. Pettengill, Lancaster, Ohio, assignor to Anchor Hocking Glass Corporation, Lancaster, Ohio, a corporation of Delaware

Original design application June 1, 1966, Ser. No. 2,506. Divided and this application Sept. 26, 1967, Ser. No. 8,736

Term of patent 14 years

(Cl. D9—50)

FIG. 1.

FIG. 2.

FIG. 1 is a front elevational view of a jug or similar article showing my new design with the rear being the same in appearance except for the reverse position of the handle;

FIG. 2 is a sectional view taken along line 2—2 of FIG. 1.

The dominant features of my design reside in the portions shown in full lines.

The present application is a division of my copending design application Ser. No. 2,506, filed June 1, 1966.

I claim:

The ornamental design for a jug or similar article, substantially as shown and described.
